Patented Sept. 13, 1921.

FIG. 1.

FIG. 2.

Inventor

Joe E. Barry

UNITED STATES PATENT OFFICE.

JOE E. BARRY, OF GRANVILLE, NORTH DAKOTA.

AUTOMOBILE-SPRING.

1,390,326.

Specification of Letters Patent. Patented Sept. 13, 1921.

Application filed March 16, 1921. Serial No. 452,694.

To all whom it may concern:

Be it known that I, JOE E. BARRY, a citizen of the United States, residing at Granville, in the county of McHenry and State 5 of North Dakota, have invented certain new and useful Improvements in an Automobile-Spring, of which the following is a specification.

This invention relates to automobile 10 springs and more particularly to a device for resiliently supporting an automobile from the axle in an improved and efficient manner.

One of the objects of the invention is to 15 provide an improved automobile spring which will utilize a plurality of telescoping cylinders operating in conjunction with superposed coil springs whereby the shock and jars occasioned by unevenness in the 20 roadway will be absorbed by the springs.

Other objects of the invention will appear upon consideration of the following detail description and accompanying drawing, wherein:—

25 Figure 1 is a front elevation of an automobile showing the invention applied, and Fig. 2 is a vertical section through one of the springs constituting the invention.

Referring to the drawing by numerals the 30 base flange 1 is provided with a vertically disposed stationary cylinder 2 which may be of any preferred length and which has its top closed by the upper wall 3. This wall is provided with a stuffing box 4 through which a piston rod 5 extends and the upper end of the piston rod is secured 35 as indicated at 6 to the top end wall 7 of an outside movable cylinder 8, which embraces the stationary cylinder 2 and has a sliding fit thereon. From the outside cylinder 8 the supporting bar 9 extends which is adapted to support the chassis of the automobile whereby the body may be mounted in the usual manner. Arranged within the 40 stationary cylinder 2 is the co-acting cylinder 10, which is substantially half the length of the stationary cylinder 2 and has a sliding fit thereon. The lower end of the co-acting cylinder 10 is closed by the lower 45 end wall 11 and a coil spring 12 is interposed between the wall 11 and the bottom of the stationary cylinder 2. Arranged within the co-acting cylinder 10 is another 50 movable cylinder termed the equalizing cyl-

inder 13 which is somewhat shorter in 55 length than the co-acting cylinder 10 as shown in the drawings. The upper ends of each of the cylinders 10 and 13 are open as shown and the piston rod 5 extends downwardly into these cylinders and carries a 60 piston 14 which is adapted to reciprocate in the equalizing cylinder 13 when the piston rod 5 moves longitudinally through the stuffing box 4.

A spring 15 is interposed between the 65 bottom of the equalizing cylinder 13 and the end wall 11 of the co-acting cylinder 10. Another coil spring 16 is interposed between the piston 14 and the closed end of the 70 equalizing cylinder 13 while a shock absorbing spring 17 is interposed between the end wall 3 of the stationary cylinder and the top of the piston 14.

A quantity of oil is contained in the lower 75 end of the stationary cylinder 2 as indicated by the space 18 and the closed end wall of the co-acting cylinder 10 and the equalizing cylinder 13 are provided with oil openings 19 and 20 whereby oil may be 80 passed into the cylinders from the lower end of the stationary cylinder 2 when the device is in operation.

It will be apparent from the above description that the cylinders have sliding contact with each other and the springs arranged in superposed relation are adapted to coöperate so that all shocks and jars will be entirely eliminated when the apparatus is employed to support the vehicle from the 85 axle of the automobile. The base flanges 1 are mounted upon the axles as shown to advantage in Fig. 1 and it will be obvious 90 that four of the devices will be employed, two being mounted on the front axle and two being mounted on the rear axle so that 95 the automobile body will be supported by the springs at the four corners of the body.

Minor changes may be made in the details of construction without departing from the spirit of the invention or the scope of the 100 claims hereunto appended.

What is claimed is:—

1. An automobile spring comprising a plurality of telescoping cylinders, the cylinders having certain ends closed, coil 105 springs interposed between the closed ends of the cylinders, a sliding outside cylinder provided with a supporting bar, a piston

carried by the said outside cylinder and extending into the innermost sliding cylinder, and coil springs engageable with the said piston and with the ends of the said cylinders.

2. A device of the character described comprising a plurality of telescoping cylinders including a stationary cylinder, an outside sliding cylinder embracing the stationary cylinder, a supporting rod carried by the sliding cylinder, a piston suspended from the closed end of the sliding cylinder, the said piston being extended into the interior of the said telescoping cylinders, and coil springs arranged on the interior of the said cylinders.

3. An automobile spring comprising a stationary cylinder, an outside sliding cylinder embracing the stationary cylinder, and equipped with a supporting bar, a piston rod secured to the top of the sliding cylinder and provided with a piston, a co-acting cylinder arranged within the stationary cylinder, an equalizing cylinder arranged within the co-acting cylinder, and coil springs interposed between the ends of the cylinders

and other springs engageable with the opposite sides of the said piston.

4. An automobile spring comprising a stationary cylinder, an outside sliding cylinder embracing the stationary cylinder, and equipped with a supporting bar, a piston rod secured to the top of the sliding cylinder and provided with a piston, a co-acting cylinder arranged within the co-acting cylinder, an equalizing cylinder arranged within the co-acting cylinder, and coil springs interposed between the ends of the cylinders and other springs engageable with the opposite sides of the said piston, the lower end of the stationary cylinder being provided with an oil space adapted to contain a quantity of oil the closed ends of the inner cylinders being provided with oil ports whereby the oil may be passed into the inner cylinders.

In testimony whereof, I have affixed my signature in the presence of two witnesses.

JOE E. BARRY.
